FINGERNAIL CLIPPER

George P. Davis, Durham, N. C.

Application December 6, 1948, Serial No. 63,829

1 Claim. (Cl. 30—28)

1

This invention relates to finger nail clippers.

An object of this invention is to provide an improved clipper embodying complementary blades with handles extending from the blades, and a spring carried by one of the handles engaging the other handle for constantly urging the blades to open position.

Another object of this invention is to provide in a device of this kind, an improved means for locking the blades in closed position, the locking means also forming a file and overlying one of the handles when in locked position.

A further object of this invention is to provide a nail clipper which is of simple construction so that it can be made at relatively low cost.

With the above and other objects in view, my invention consists in the arrangement, combination and details of construction disclosed in the drawing and specification, and then more particularly pointed out in the appended claim.

In the drawing,

Figure 1 is a plan view of a nail clipper or trimmer constructed according to an embodiment of my invention, showing the device in open operative position.

Figure 2 is a sectional view taken on the line 2—2 of Figure 1.

Figure 3 is a detail side elevation partly broken away and in section, of the device in closed position.

Figure 4 is a sectional view taken on the line 4—4 of Figure 2.

Referring to the drawing, the numerals 10 and 11 designate generally a pair of complementary clipper blades. The blade 10 comprises the stationary blade and is carried by a pair of rearwardly extending elongated bars 12 which are disposed in spaced apart parallel relation.

The blade 11 which is pivotally mounted on a pivot member 13 extending between the two bars 12, has extending rearwardly therefrom an integral longitudinally bowed handle or lever 14. The two bars 12 adjacent the rear thereof are connected together by means of a connecting plate 15 which has fixed to the lower side thereof the rear end of a longitudinally bowed spring 16. A rivet or other fastening means 17 secures the rear end of the spring 16 to the plate 15. The handle or lever 14 tapers in thickness from the forward to the rear end thereof and forms a shoulder 18 closely adjacent the pivot 13 and the free or forward end of the spring 16 is adapted when the device is in closed inoperative position to engage in the space formed by the shoulder 18.

The two bars 12 have pivotally secured thereto

a file 19 and the rear ends of the bars 12 are each formed with an ear 20. The file 19 is also formed with a pair of right angularly disposed ears 21 and a pivot pin 22 extends through the ears 20

5 and 21 so as to pivotally secure the file 19 to the rear ends of the bars 12. When the handle or lever 14 is in inoperative position, this lever is adapted to engage between the ears 20 and to overlie the pivot pin 22, as shown in Figure 3.

10 At this time the file 19 is swung forwardly to overlying position so that the rear portion of the file 19 will form a locking means for locking the lever 14 in inoperative position with the two blades 10 and 11 in closed or contacting position. In order to 15 open the clippers, the file 19 is swung upwardly and rearwardly to the position shown in Figure 2, thereby releasing the lever 14 which is swung upwardly to open position by means of the spring 16.

20 This clipper being of relatively simple construction will not readily get out of order and the locking means for the pivoted blade and handle will not become damaged or broken as is the case with clippers of present construction which require the lateral shifting of the lever for engagement with a fixed keeper or lock.

I do not mean to confine myself to the exact details of construction herein disclosed, but claim all variations falling within the purview of the appended claim.

30 What I claim is:

A nail clipper comprising an open bottomed channel shaped member having a clipper blade extending therefrom, a second member including 35 an oppositely disposed clipper blade pivotally connected between the sides of said channel shaped member at a point adjacent said first mentioned clipper blade; a connecting plate between the sides of said first mentioned member at the end 40 thereof opposite the blade, a leaf spring secured to the underside of said plate extending upwardly between the sides of said channel shaped member and having one end projecting beyond said plate, a right angled shoulder on the under side of said 45 second member adapted to abut the other end of said spring, an extending plate of a length substantially equal to said channel shaped member having apertured lugs with rounded extremities on one end thereof, a pivot pin extending through 50 the apertures in said lugs and the ends of the side walls of said channel shaped member outwardly of said first mentioned member pivotally connecting said last mentioned plate thereto, said end of said spring when said last mentioned plate 55 overlies said channel shaped member abutting

said pivot pin, whereby the bias of said end of said spring resists pivotal movement of said last mentioned plate, said last mentioned plate being adapted to overlie said second member to hold the same in said channel-shaped member in the space provided by said shoulder and, hence, said jaws in closed position.

GEORGE P. DAVIS.
